MULTICOLOR PRINTING MACHINE

Arthur Dressel, Hollis, N. Y., assignor to R. Hoe
& Co., Inc., New York, N. Y., a corporation of
New York

Application March 6, 1941, Serial No. 382,085

16 Claims. (Cl. 270—5)

This invention relates to printing machines, and more particularly to multicolor web printing machines.

Heretofore various arrangements of printing units and cooperating components have been provided to produce multicolor products. Some of these arrangements incorporate a common impression cylinder, about which a number of plate or form cylinders are disposed, and, in others, a plurality of superposed color printing units are provided, and they are arranged so that various web runs are possible. Various other arrangements are also provided, but in each instance, the operating and web run flexibility is somewhat limited. More recently, standard perfecting newspaper units with additional form cylinders have been employed to produce multicolor printing, but although such arrangements have proved relatively satisfactory, they too lack the operating and web run flexibility now commercially demanded.

It is, therefore, an object of this invention to provide a line of printing units to produce multicolor products, the units being constructed and arranged to afford the maximum operating and web run flexibility.

Another object of this invention is to provide a printing machine incorporating a folder and a plurality of units in line, certain of the units being standard perfecting units, and others being standard perfecting units provided with additional color printing cylinders, the arrangement being such as to afford maximum operating and web run flexibility.

It is also an object of this invention to provide a multicolor web printing machine of generally improved construction and arrangement, whereby the device will be simple, durable, and inexpensive in construction, as well as convenient, practical, serviceable and efficient in its use.

With the foregoing and other objects in view, which will appear as the description proceeds, the invention resides in the combination and arrangements of parts and in the details of construction hereinafter described and claimed, it being understood that various changes in form, proportion and minor details of construction may be made within the scope of the claims without departing from the spirit of the invention.

For a complete disclosure of the invention, a detailed description thereof will now be given in connection with the accompanying drawings forming a part of the specification, wherein:

Figure 1 is a diagrammatic side elevation de-

picting a folder and a plurality of printing units in line.

Figure 2 is a diagrammatic indication of the products produced by the arrangement disclosed in Figure 1.

Figure 3 is a diagrammatic side elevation similar to Figure 1, but depicting a different web run.

Figure 4 is a diagrammatic indication of the products produced by the arrangement disclosed in Figure 3.

Figure 5 is a diagrammatic side elevation similar to Figures 1 and 3, but depicting another web run.

Figure 6 is a diagrammatic indication of the products produced by the arrangement disclosed in Figure 5.

Figure 7 is a diagrammatic side elevation similar to Figures 1, 3, and 5, but depicting still another web run.

Figure 8 is a diagrammatic indication of the products produced by the arrangement disclosed in Figure 7.

Figure 9 is a diagrammatic side elevation similar to Figures 1, 3, 5, and 7, but depicting still another web run.

Figure 10 is a diagrammatic indication of the products produced by the arrangement disclosed in Figure 9.

Referring to the drawings in which similar reference characters designate corresponding parts, there is depicted an improved printing machine construction and arrangement which includes a plurality of standard perfecting printing units, a plurality of three-impression printing units and a folder arranged in line. In the present illustration, 7 units are provided, and the first unit A is a perfecting newspaper printing unit comprising two printing couples 11 and 12, and the couple 11 includes an impression cylinder 13 and a form or plate cylinder 15, and the couple 12 includes an impression cylinder 13^a and cooperating form cylinder 15^a. The second unit B is a special three-impression unit, and includes two printing couples 16 and 17 of standard construction. The printing couple 16 includes the usual impression cylinder 13 and plate or form cylinder 15, and the couple 17 includes the conventional impression cylinder 13^a and cooperating form cylinder 15^a. The printing couple 16 is also provided with an additional plate or form cylinder 18 which runs in cooperable engagement with the impression cylinder 13 to provide a printing triple. The printing unit A incorporates the conventional inking mechanism for the plate or form cylinders, and also a suitable drive mechanism.

The drive mechanism is, however, so constructed and arranged that the impression cylinder 13^a and form cylinder 15^a of the printing couple 12 are reversibly driven. Inasmuch as the inking mechanism here referred to is of standard construction which is well understood by those skilled in the art, such inking mechanism has not been illustrated in the drawings in this application. The reversing driving mechanism is also well understood by those skilled in the art, and such an arrangement is disclosed in the Lamatsch Patent No. 2,102,631, therefore, the drive mechanism for the units disclosed in this application has not been illustrated.

The three-impression printing unit B is similar to the perfecting unit A except the provision of the additional plate or form cylinder 18 and the conventional inking mechanism, not shown, for this cylinder. The three-impression unit B is constructed and arranged so that the form cylinders 15 and 18 and the cooperating impression cylinder 13 are driven for reversible operation.

The third printing unit C is similar to the standard perfecting unit A, and it includes two printing couples 20 and 21, and the printing couples include impression cylinder 13—13^a and form cylinder 15—15^a. The impression cylinder 13^a and form cylinder 15^a of the printing couple 21 are reversibly driven.

The fourth unit D is located in line adjacent the unit C, and this unit is a special three-impression unit similar to the unit B, and includes printing couples 22 and 23, and an additional form or plate cylinder 25 which runs in cooperative relation with the impression cylinder 13 of the printing couple 22. In this unit the form cylinders 15 and 25 and cooperating impression cylinder 13 are reversibly driven.

A former folder 26 of the conventional construction is positioned in the line adjacent the unit D, and webs are led from the units of this line to the folder through suitable guide instrumentalities to be hereinafter described.

A perfecting printing unit E provides the fifth unit, and it is located in the line adjacent the folder 26. This unit includes two printing couples 27 and 28, and the printing couple 28 is driven for reversible operation.

A three-impression perfecting printing unit F is located in the line adjacent the standard unit E and this unit provides the sixth printing unit of the line. It includes two printing couples 30 and 31, and each couple, in conformity with the arrangement of the other printing units, includes an impression cylinder 13 or 13^a and a form cylinder 15 or 15^a. A separate form or plate cylinder 32 cooperably engages the impression cylinder 13 of the printing couple 30. In this unit the form cylinders 32 and 15 and the cooperating impression cylinder 13 are reversibly driven, in the manner hereinbefore disclosed.

The seventh unit G is next positioned in the line adjacent the unit F, and this unit includes two printing couples 36 and 37 having impression cylinders 13—13^a and form cylinders 15—15^a. An additional form or plate cylinder 38 runs in cooperative engagement with the impression cylinder 13^a of the printing couple 37. In this unit the impression cylinder 13 and form cylinder 15 70 of the printing couple 36 are reversibly driven.

Each plate or form cylinder may be supplied by the usual inking mechanism, hereinbefore referred to, with black ink or ink of any preferred color, and it is to be understood, of course, that 75

the ink supplied to each form cylinder may be changed to meet color requirements.

In the arrangement depicted in Figure 1, the outermost web W¹, that is, the upper or top web which passes over the drag roller 40 in its run to the former of the folder 26, is directed by guide rollers 41 through the printing couples 27 and 28 of the fifth unit E, where a black impression is printed on the first or obverse side of the web W¹, and a color impression is printed on the second or reverse side of this web. The web W¹ is then guided by rollers 42 through the three-impression unit F, where two colors and a black impression are printed on the second or reverse side of the web, so that the web now has one impression on its first or obverse and four impressions on its second or reverse side, as indicated in the diagrammatic Figure 2. The web W¹ is led from the special unit F over guide rollers 43 to the drag roller 40, where it is slit and then led down over the formers of the folder 26, in conformity with the usual practice.

The second outermost web W², that is, the second web from the top which passes down over the drag roller 40 in its run to the formers, is led around rollers 45 through the three-impression unit G, where a color impression is printed on the first or obverse side of the web, and two color impressions are printed on the second or reverse side of the web, as indicated in the diagrammatic Figure 2. After passing through the special printing unit G, the web W² is led around guide rollers 46 and over the drag roller 40, where it is slit into narrower webs or ribbons, and the ribbons are then directed down over the formers of the folder 26, in conformity with the usual practice.

The next outermost web W³ is led around guide rollers 47 through the three-impression printing unit B, where a color impression is printed on the first or obverse side of the web, and then two color impressions are printed on the second or reverse side of the web. This web is then led around guide rollers 48 through the perfecting printing unit A, where two additional color impressions are printed on the second or reverse side of the web, so that the web now has four colors imprinted on one side and one color on the other, as indicated in Figure 2. After web W³ passes through the unit A, it is led around guide rollers 50 to the drag roller 40, and then to the folder, in conformity with the usual practice.

The innermost web W⁴ is led around guide rollers 51 through the perfecting printing unit C, where a black impression is printed on the first or obverse side of the web, and a color impression is printed on the second or reverse side of the web. Web W⁴ is then guided from the unit C around guide rollers 52 through the three-impression printing unit D, where two colors and a black impression are printed on the second or reverse side of the web, so that this web now has one impression on one side and four impressions on the other, as indicated in Figure 2. After the web W⁴ passes through the special unit D, it is led around guide rollers 53 to the drag roller 40, where it is slit and finally led down the formers of the folder 26, in conformity with the usual practice.

From the foregoing, it is observed that in the web runs disclosed in Figure 1, the outermost web W¹ has one impression printed on one side and four on the other; the next outermost web W² has one impression printed on one side and two on the other; and the third web W³ has four

impressions imprinted on one side and one on the other; while the last or innermost web W^4 has one impression printed on one side and four impressions on the other.

In the arrangement depicted in the drawings of this application, turner bars 55, of the conventional construction, are provided, and when these turner bars are employed, the webs may be slit and led from one side of the press to the other, so that different combinations of webs may be run down the formers of the folder, but inasmuch as this phase of the disclosure forms no part of the invention apart from the arrangement disclosed, it has not been further illustrated.

In the arrangement disclosed in Figure 3, the first or outermost web W^1 is first led through the three-impression unit F, where one impression is printed on the first or obverse side and two impressions are printed on the second or reverse side. This web is then led through the perfecting printing unit E, where two additional impressions are printed on the second or reverse side, so that the web now has four impressions imprinted on one side and one on the other, as indicated in the diagrammatic Figure 4. After printing, this web is led over the drag roller 40 and down the formers of the folder 26, in conformity with the usual practice.

The second outer web W^2 is led through the three-impression printing unit G, where one impression is printed on the first or obverse side of the web and two impressions are printed on the second or reverse side of the web, as indicated in the diagrammatic Figure 4. This web is then led over the drag roller 40 and down the formers of the folder.

The third web W^3 is first led through the perfecting printing unit A, where one impression is printed on the first or obverse side of the web and another impression is printed on the second or reverse side of the web. This web is then led through the three-impression printing unit B, where three additional impressions are printed on the second or reverse side of the web, so that the web now has one impression printed on one side and four impressions printed on the other. Web W^3 is then led over the drag roller 40 and down the formers of the folder 26 in the usual manner.

The fourth or innermost web W^4 is first led through the three-impression printing unit D, where one impression is printed on the first or obverse side of the web and two impressions are printed on the second or reverse side of the web. This web is then led through the perfecting unit C, where two additional impressions are printed on its second or reverse side, so that the web now has one impression printed on one side and four impressions printed on the other, as shown in the diagrammatic Figure 4. The printed web W^4 is then led over the drag roller 40 and down the formers of the folder 26 with the other printed webs.

In comparing the results produced by the arrangement shown in Figure 3 with the results produced by the arrangement depicted in Figure 1, it will be seen that the impressions printed on the faces of the web W^1 have been reversed. The side or face of the web which in one arrangement had one impression, has four in the other arrangement, and the surface on which four impressions were made in one arrangement, has one in the other arrangement. This is also true of the webs W^3 and W^4 . The impressions printed

on the opposed faces of the web W^2 are the same in both arrangements.

In the arrangement depicted in Figure 5, the first or outermost web W^1 is led through the perfecting printing unit E, where one impression is printed on the first or obverse side of the web and another impression is printed on its second or reverse side, as indicated in diagrammatic Figure 6. The printed web W^1 is then led over the drag roller 40 and down the formers of the folder 26.

The second or outermost web W^2 is first led through the three-impression printing unit F, where two impressions are printed on the first or obverse side of the web, and a single impression is printed on the second or reverse side of the web. This web is then led through the three-impression printing unit G, where three additional impressions are printed on the second or reverse side of the web, so that the web now has four impressions on one side and two on the other, as indicated in diagrammatic Figure 6. The printed web W^2 is then led over the drag roller 40 and down the formers of the folder, in conformity with the usual practice.

The third outermost web W^3 is first led through the perfecting printing unit C, where one impression is printed on the first or obverse side of the web and another impression is printed on a second or reverse side of the web. This web is then led around the impression cylinder 13 of the unit B, where two additional impressions are printed on the second or reverse side of the web, so that the web now has three impressions printed on one side and one on the other, as indicated in the diagrammatic Figure 6. The printed web W^3 is then led over the drag roller 40 and finally down the formers of the folder. The fourth or innermost web W^4 is led through the three-impression printing unit D, where one impression is printed on the first or obverse side of the web and two impressions are printed on the second or reverse side of the web, as indicated in the diagrammatic Figure 6. The printed web W^4 is then led over the drag roller 40 and down the formers of the folder in the usual manner.

In reviewing the results products by the arrangement depicted in Figure 5, it will be observed that the first or outermost web W^1 has a single impression printed on one side and a single impression printed on the other; the second outermost web W^2 has two impressions on one surface and four impressions on the other; the third outermost web W^3 has three impressions printed on one side thereof and one impression printed on the other; and the fourth or innermost web W^4 has two impressions printed on one side and one impression on the other.

In the arrangement depicted in Figure 7, the first or outermost web W^1 is led through the perfecting printing unit E, where one impression is printed on the first or obverse side of the web and another impression is printed on its second or reverse side, as indicated in the diagrammatic Figure 8. The printed web W^1 is then led over the drag roller 40 and down the formers of the folder. The second outermost web W^2 is first led through the three-impression printing unit G, where two impressions are printed on the first or obverse side of the web and a single impression is printed on its second or reverse side. This web is then led around the impression cylinder 13 of the unit F, where two additional impressions are printed on the second or reverse

side of the web, so that the web now has two impressions printed on one side and three on the other, as indicated in diagrammatic Figure 8. The printed web W^2 is then led over the drag roller 40 and down the formers of the folder 26. 5 The third outermost web W^3 is first led through the three-impression printing unit B, where one impression is printed on the first or obverse side of the web and two impressions are printed on its second or reverse side. This web is then led around the impression cylinder 13a of the printing unit C, where an additional impression is printed on the first or obverse side of the web, so that the web now has two impressions printed on one surface and two impressions printed on the other, as indicated in diagrammatic Figure 8. The fourth or innermost web W^4 is led through the three-impression printing unit D, where one impression is printed on the first or obverse side of the web and two impressions are printed on the second or reverse side, as indicated in diagrammatic Figure 8. The printed webs W^3 and W^4 are finally led over the drag roller 40 and down the formers of the folder 26, in conformity with the usual practice.

In the arrangement depicted in Figure 9, the outermost web W^1 is first led around the impression cylinder 13a of the three-impression printing unit F, where one impression is printed on the first or obverse side of the web. This web is then led through the three-impression printing unit G, where three additional impressions are printed on the first or obverse side of the web. The web W^1 is then led around the impression cylinder 13 of the unit F, where two impressions are printed on the second or reverse side of the web. From this point web W^1 is led through the perfecting printing unit E, where two additional impressions are printed on the second or reverse side of the web, so that the web now has four impressions printed on one side and four on the other, as indicated in diagrammatic Figure 10. The printed web W^1 is finally led over the drag roller 40 and down the formers of the folder 26. The second or innermost web W^2 is first led around the impression cylinder 13 of the unit B, where two colors are printed on the first or obverse side of the web, and this web is then led through the perfecting printing unit A, where two additional impressions are printed on the same side thereof. From this point the web W^2 is led around the impression cylinder 13a of the perfecting unit C, where an impression is printed on its second or reverse side, and then this web is led through the three-impression printing unit D, where three additional impressions are printed on the second or reverse side of the web, so that the web now has four impressions printed on one side and four impressions printed on the other, as indicated in diagrammatic Figure 10. The printed web W^2 is finally led over the drag roller 40 and down the formers of the folder 26, in conformity with the usual practice.

From the foregoing it will be observed that the arrangement disclosed in this invention provides maximum flexibility, in that any selected web may be run through any selected printing couple or printing unit, or any combination thereof, and then the printed web may be run directly to the formers of the folder without passing through a circuitous path, or without passing under the folder. Furthermore, various combinations may be produced by different web runs with the same 75

colors remaining on the form cylinders, or different color combinations may be easily produced by employing the same web runs and utilizing different colors on selected form cylinders.

The arrangement preferably provides for an old number of units and a folder in a line, with certain of the units being located at one side of the folder and others at the opposite side. The units at one side of the folder are so arranged 10 that a standard perfecting unit is positioned immediately adjacent the folder and a three-impression unit is positioned immediately adjacent the standard unit at a location away from the folder. On the opposed side of the folder, the units are reversed, so that a three-impression unit is positioned immediately adjacent the folder, and then a standard perfecting unit is positioned adjacent the three-impression unit but at a location removed from the folder. At this side 15 of the former this arrangement is preferably repeated so that the units are arranged in pairs and each pair including a three-impression printing unit and a standard perfecting printing unit.

Inasmuch as this arrangement incorporates 20 standard units and slightly altered standard units arranged in pairs with a folder in line, a great saving in initial cost is effected, and, furthermore, since standard units are employed, the obsolescence cost is greatly reduced because of the greater resale and trade-in value of these units. The utility of the press line is greatly increased, 25 because the arrangement may be employed for regular black press or newspaper production. The arrangement is such that less time is required to thread the webs, and, consequently, less effort on the part of the operators is required. The units are capable of running at a high speed, and since they are all located on a common floor 30 level, the entire line of units is relatively easy to operate and maintain, and all adjustments both preparatory and operational, are made from the same floor level. The arrangement is such that each completely printed web is led directly from the final printing cylinders to the folder, thus 35 eliminating long and complicated web runs.

It will be understood that the invention may be embodied in other specific forms without departing from the spirit or essential attributes thereof, and it is therefore desired that the present 40 embodiment be considered in all respects as illustrative and not restrictive, and it will be further understood that each and every novel features and combination present in or possessed by the mechanism herein disclosed forms a part of the 45 invention included in this application.

Having thus described my invention, what I claim as new and useful is:

1. In a printing machine having a folder and perfecting printing units arranged in line on one floor level, a first printing unit adjacent the folder and having two form cylinders and two impression cylinders arranged as a standard perfecting printing unit and adapted to print one color on each side of a web, a second printing unit positioned beyond the first unit with relation to the folder and having two form cylinders and two impression cylinders arranged as a standard perfecting printing unit, an additional form cylinder on the second printing unit arranged in 50 cooperable relation to one of the impression cylinders, and means for reversing the direction of rotation of one of the printing couples or triples of each unit, whereby a web may be led through both units to first print one color on one side and subsequently print four colors on the other side,

and alternatively, to first print four colors on the one side and subsequently print one color on the other side.

2. In a printing machine, a number of pairs of printing units and a folder arranged in line on one floor level, the folder and units being so disposed that at least one pair of units is located in the line at each side of the folder, each pair of units comprising a perfecting unit having two impression and two form cylinders arranged as a standard perfecting printing unit, and a three-impression unit having two impression and two form cylinders arranged as a standard perfecting printing unit and an additional form cylinder positioned in cooperable relation with one of the impression cylinders so that two of the form cylinders of each three-impression unit operably engages a single impression cylinder.

3. In a printing machine, a number of pairs of printing units and a folder arranged in line on one floor level, the folder and units being so disposed that at least one pair of units is located in the line at each side of the folder, each pair of units comprising a perfecting unit having two impression and two form cylinders arranged as a standard perfecting printing unit, and a three-impression unit having two impression and two form cylinders arranged as a standard perfecting printing unit and an additional form cylinder positioned in cooperable relation with one of the impression cylinders so that two of the form cylinders of each three-impression unit operably engages a single impression cylinder, and means for reversibly driving certain cylinders of each unit.

4. In a printing machine, a number of pairs of printing units and a folder arranged in line on one floor level, the folder and units being so disposed that at least one pair of units is located in the line at each side of the folder, each pair of units comprising a perfecting unit having two impression and two form cylinders arranged as a standard perfecting printing unit and a three-impression unit having two impression and two form cylinders arranged as a standard perfecting printing unit and an additional form cylinder positioned in cooperable relation with one of the impression cylinders so that two of the form cylinders of each three-impression unit operably engages a single impression cylinder, the units at one side of the folder being so disposed that the perfecting unit of each pair is located adjacent the folder and the three-impression unit away from the folder, and at the opposed side of the folder the units of each pair of units are so disposed that the three-impression unit is located adjacent the folder and the perfecting unit away from the folder. 45 50 55

5. In a printing machine, a number of pairs of printing units and a folder arranged in line on one floor level, the folder and units being so disposed that at least one pair of units is located in the line at each side of the folder, each pair of units comprising a perfecting unit having two impression and two form cylinders arranged as a standard perfecting printing unit and a three-impression unit having two impression and two form cylinders arranged as a standard perfecting printing unit and an additional form cylinder positioned in cooperable relation with one of the impression cylinders so that two of the form cylinders of each three-impression unit operably engages a single impression cylinder, the units at one side of the folder being so disposed that the perfecting unit of each pair is located adjacent

the folder and the three-impression unit away from the folder, and at the opposed side of the folder the units of each pair of units are so disposed that the three-impression unit is located adjacent the folder and the perfecting unit away from the folder, and means for reversibly driving certain cylinders of each unit.

6. In a printing machine, a number of pairs of printing units, a single unit and a folder arranged in line on one floor level, the folder and units being so disposed that at least one pair of units is located in the line at one side of the folder and a pair of units and a single unit located in the line at the opposed side of the folder, each pair of units comprising a perfecting unit having two impression and two form cylinders arranged as a standard perfecting printing unit and a three-impression unit having two impression and two form cylinders arranged as a standard perfecting printing unit and an additional form cylinder positioned in co-operable relation with one of the impression cylinders so that two of the form cylinders of each three-impression unit operably engages a single impression cylinder.

23 7. In a printing machine, a number of pairs
of printing units, a single unit and a folder ar-
ranged in line on one floor level, the folder and
units being so disposed that at least one pair of
30 units is located in the line at one side of the
folder and a pair of units and a single unit lo-
cated in the line at the opposed side of the folder,
each pair of units comprising a perfecting unit
having two impression and two form cylinders
35 arranged as a standard perfecting printing unit
and a three-impression unit having two impres-
sion and two form cylinders arranged as a stand-
ard perfecting printing unit and an additional
form cylinder positioned in cooperable relation
40 with one of the impression cylinders so that two
of the form cylinders of each three-impression
unit operably engages a single impression cylin-
der, and means for reversibly driving certain cyl-
inders of each unit.

45 8. In a printing machine, a number of pairs of printing units and a folder arranged in line on one floor level, the folder and units being so disposed that at least one pair of units is located in the line at one side of the folder and a plurality of pairs of units are located in the line at the opposed side of the folder, each pair of units comprising a perfecting unit having two impression and two form cylinders arranged as a standard perfecting printing unit and a three-impression unit having two impression and two form cylinders arranged as a standard perfecting printing unit and an additional form cylinder positioned in cooperable relation with one of the impression cylinders so that two of the form cylinders of each three-impression unit operably engages a single impression cylinder.

9. In a printing machine, a number of pairs of printing units and a folder arranged in line on one floor level, the folder and units being so disposed that at least one pair of units is located in the line at one side of the folder and a plurality of pairs of units are located in the line at the opposed side of the folder, each pair of units comprising a perfecting unit having two impression and two form cylinders arranged as a standard perfecting printing unit and a three-impression unit having two impression and two form cylinders arranged as a standard perfecting printing unit and an additional form cylinder positioned in cooperable relation with one of the

16. In a printing machine, seven printing units and a folder in line on one floor level, the units being so arranged that at least one pair of units is located in the line at each side of the folder, each pair of units comprising a perfecting unit having two impression and two form cylinders arranged as a standard perfecting printing unit and a three-impression unit having two impression and two form cylinders arranged as a standard perfecting printing unit and an additional form cylinder positioned in cooperable relation with one of the impression cylinders so that two of the form cylinders of each three-impression

unit operably engages a single impression cylinder, the units in the line at one side of the folder being so disposed that the perfecting unit of each pair is located adjacent the folder and the three-impression unit away from the folder, and at the opposite side of the folder each pair of units are so disposed that the units of the three-impression unit is located adjacent the folder and the perfecting unit away from the folder, and means for reversibly driving certain cylinders of each unit.

ARTHUR DRESSEL.
